AWNINg CONTROL MECHANISM

Walter G. Armstrong, Lakewood, N. Y.

Application June 16, 1951, Serial No. 231,965

7 Claims. (Cl. 160—72)

1

This invention relates to awnings formed from strips that are interlocked in a manner to facilitate being rolled into and out of position of use. More particularly, the invention relates to structure by which to enable the manipulation of such awnings.

Awnings of the type to which the invention is more particularly applicable are formed from a multiplicity of narrow metal strips that are slightly curved in cross section and include suitably rolled side edges that interlock in a manner to permit sidewise rolling into and out of operative position. The strips of such an awning, of course, extend transversely of the direction of operation, one endmost strip being attached to a building wall, or door, or window casing, and the other endmost strip jointed to a roller that is provided with an internal torsion spring which normally urges the awning, in its entirety, into a rolled up, out-of-use position.

It has been the practice in providing manipulating mechanisms for awnings of this type to locate them at some exterior position adjacent the awning, thus necessitating the opening of a door or window each time it is desired to roll the awning into operative or inoperative position. In some instances these awnings are applied to non-opening windows, such as so-called "picture windows" and, under such circumstances, it becomes necessary to step out of doors in order to roll or unroll the awning. Under such circumstances, desirable and repeated adjustment of an awning can only be accomplished at such inconvenience as to render its use wholly unsatisfactory. Additionally, even through access to the awning operating mechanism may be had by opening a window or door, it is apparent that a certain amount of time is required in the operation of raising or lowering the awning and, under adverse weather conditions, snow or rain can enter the building during this operation. The result of such an inconvenient operative arrangement for awnings undoubtedly accounts for a certain measure of sales resistance to the installation of this and other types of awnings.

It is a purpose and object of the present invention to provide a mechanism for the inside control and operation of exterior awnings of the type that are rolled into and out of position of use.

Another object of the invention lies in the provision of a simple and easily installed mechanism that includes parts of such proportions and appearance as to be relatively inconspicuous beneath or adjacent an interior window or door frame trim.

2

A further and important object of the invention lies in the provision of an awning operating control that may be installed beneath almost any type of window sill, access thereto being had by the removal of a concealing cover plate.

Other objects and advantages of the invention will be more fully understood from a consideration of the following specification, taken in conjunction with the accompanying drawings; and in which

Fig. 1 is a perspective view of an awning of the rollable slat type, held in operative positive by interior control mechanism constituting the present invention;

Fig. 2 is a greatly enlarged transverse vertical sectional view of the lower portion of a window frame, fitted with the structure of the invention;

Fig. 3 is an end view of a cover plate that encloses the awning control cable receiver located beneath the interior sill of a window;

Fig. 4 is a front elevational view of the cover plate shown in Fig. 3;

Fig. 5 is a plan view of the cable receiver with the cover plate removed;

Fig. 6 is a side elevational view with the cover plate partly broken away to disclose certain details of the cable receiver;

Fig. 7 is an enlarged fragmentary view, partly in section and elevation, showing the torsion spring roller and its connection with the awning control cable; and

Fig. 8 is a transverse sectional view, taken substantially as suggested by the lines 8—8 of Fig. 7.

Referring more particularly to the drawing, the reference numeral 10 is employed to generally designate an awning to which the present invention is applicable. For the purpose of a clearer understanding of the invention, it is necessary to show and describe one particular form of awning found to be well suited to manipulative control by the structure of the present invention. The awning 10 is formed from a plurality of slats 11. Each slat is relatively narrow, extends transversely of the direction of roll of the awning, and in cross section is slightly bowed, substantially as suggested in Fig. 8. The lower edge of each slat terminates in a downwardly or underneath curved flange 12, whereas the upper edge is curved to provide a recess 13, together with a curved interlocking flange 14. The flange 12 of one slat interfits the flange 14 of the next adjacent slat, a pair of such interlocked slats being edgewise relatively pivotal to an extent sufficient to enable rolling an awning about a roller 16.

Purely by way of illustrating one form of mechanism for effecting rolling the awning, attention is directed to the construction of the roller 16. This roller consists of a tube 17, closed at its ends by caps 18 and 19. Cap 18 is permanently secured to one end of tube 17 and includes a central boss 21 that extends into the tube. The end of this cap is centrally recessed to provide a bearing opening for a pin 22. This pin is carried by an end bracket 23 that is joined, in any suitable manner, to one of the two swingable rods 24. Cap 19 is also secured to the tube 17, the central portion thereof having an opening, the walls of which provide a bearing for a shaft 26. The outer end of this shaft is pinned or keyed to the other bracket 23. The shaft 26 extends substantially the full length of the tube 17 and finds a bearing at its other end in the boss 21. Adjacent the cap 19, a collar 27 is pinned or keyed to the shaft 26. A torsion spring 28 encircles the shaft 26 and is secured at one end to the boss 21, and at its other end, to the collar 27. From the structure described, it is evident that relative rotation of roller and shaft 26 increases or decreases tension of the spring 28. The other end of each rod 24 may be mounted for pivotal movement in a bracket 29, attached to the exterior casing 31 of a window 32. The lowermost slat 11 is secured in any conventional manner, to the roller 16, whereas the uppermost slat is attached to the header of the casing 31. It will be evident from the foregoing that with the awning in the position shown in Fig. 1 and the spring 28 under tension, such tension will tend to cause the roller to rotate about shafts 22 and 26 in a counter-clockwise direction, as viewed in Fig. 8. Such rotation of the roller and the consequent shortening of the awning, swings rods 24 upwardly against the casing 31 with the awning in a substantially completely rolled up position.

Attention is now particularly directed to the structure of the invention as applied to a conventional window. This window includes the usual outer sill 33, inner sill 34, and inner apron 36. On the outer face of the building wall 37, directly beneath sill 33, is secured a bracket 38. This bracket includes a pair of spaced upstanding flanges 39 which serve to mount the shaft of a pulley 41. Centrally of the bracket is an opening through which the rolled end 42 of a tube 43 projects. This tube extends completely through the building wall and apron 36 and terminates in a rolled edge 44 on the base plate 46 of a cable receiver 47. The base plate (see Fig. 5) takes the form of an elongated oval and includes a marginal upstanding rim 48. On the exact center of the base plate is an upstanding post 49 which is drilled and tapped substantially as shown. It will be noted that the rolled end 44 of the tube 43 is located directly beneath the post 49. Slightly above and to one side of the post 49 is a cable locking flange 51 which, in the present instance, is struck up from the receiver base 46. Substantially midway between the post 49 and the ends of the receiver are cable receiving cleats 52, these cleats being preferably struck up from the base 46. Two or more openings 53 are made in the base 46 to receive screws (not shown) by which to attach said base to the apron 36.

The cable receiver 47 is to be enclosed by a cover 54. This cover comprises a top 56, from which depends a continuous side flange 57. The flange 57 is so proportioned as to fit over the flange 48 of the receiver 47. The top 56 carries a locking screw having an exposed knob-like head

58 and a screw 59 that projects through an opening in the top into engagement with the threads of the post 49. Any suitable means to secure the screw in place on the cover may be employed such, for example, as the spring pin 61. The awning cable 62 is extremely flexible and is attached at one end either to the roller 16 or to the lowermost slat 11, as found most convenient. This cable extends over the pulley 41 through tube 43 into the interior of a building, and is wrapped around the cleats 52.

For a more complete understanding of the invention it is proposed to briefly describe the operation thereof. It may be assumed that the roller spring 28 is under torsional tension and that the awning 10 is in the position shown in Fig. 1. The spring normally urges the roller to revolve and roll up the awning. However, cable 62 is wedge-locked by flange 51 and engaged with cleats 52. To raise the awning, or, rather, to allow the awning to be rolled up by releasing the tension of spring 28, the knob 58 of the cover may now be removed to expose the cable receiver. The cable end is grasped by the operator and unwound from the cleats 52, following which it is disengaged from the wedging flange 51 and allowed to pay out through the tube 43. As the slats 11 are rolled up on the roller 16, the cable will also be rolled therewith as it is paid out by the operator until the awning has reached its fully raised or out-of-use position. The remaining and now short end of the cable, exposed within a building, is wound around one or both cleats and the cover 54 is replaced and secured.

35 At any time it is desired to lower or extend the awning, it is again simply necessary to remove the cover 54 and pull inwardly on the cable. The cable being wound up with the slats effects this unrolling and, when the awning has been extended to the desired position, such an unrolling operation will have again placed the spring 28 under the necessary torsional tension. The cable is now secured under the wedge-flange 51, wrapped around the cleats 52 and the cover replaced and secured.

45 Although applicant has shown and described only one form of his invention as applied to a particular awning it will be understood that modifications of the invention may be made and applied to similar awnings, or, in fact, any awning having some form of roll-up mechanism, and that such modifications are considered as being within the scope of the invention insofar as they are set out in the annexed claims.

55 Having thus set forth my invention, what I claim as new and for which I desire protection by Letters Patent is:

1. Structure for the interior control of a spring rolled awning comprising a cable attached at one end to the spring roller of said awning, a tubular member projecting through a portion of a building wall beneath said awning, a cable receiver secured to one end of said member, a cable fastener on said receiver, a cover plate for said receiver and means for removably securing said plate on said receiver.

2. Structure for the manipulation and control of a spring rolled awning comprising a cable attached at one end to said awning, a cable receiver, means for receiving and directing said cable to the central portion of said receiver, a cable locking flange on said receiver, cleats on said receiver for supporting slack cable, and a removable cover completely enclosing said receiver and the cable thereon.

3. Structure for the interior manipulation and control of an exterior spring rolled awning comprising a cable having one end attached to said awning and rollable and unrollable therewith, a cable receiver, a tube opening at one end in said receiver and providing direction of said cable from said awning to said receiver, a cable locking flange on said receiver adjacent said tube end, cleats on said receiver for supporting portions of said cable when slack, a removable cover completely enclosing said receiver, and means for securing said cover on said receiver.

4. An awning control cable receiver adapted to be mounted on an interior building wall comprising a base plate, a cable receiving tube having one open end joined to the central part of said receiver, a cable projecting through said tube, a cable wedging and locking flange on said receiver adjacent said tube end, cleats on said plate for supporting portions of said cable when slack, a removable cover enclosing said plate, and means for securing said cover on said receiver.

5. An awning control cable receiver adapted to be mounted on an interior building wall comprising a base plate, a cable receiving tube extending through said building wall and having one open end extending through said plate, a cable projecting through said tube, a rim on said plate, an upstanding post located centrally of said plate and having a threaded opening therein, opposed cleats on said plate supporting portions of said cable when slack, a cover enclosing said post and cleats, the sides of said cover overlying said plate rim, a screw carried by and projecting through said cover, said screw being engageable with said threaded opening.

6. An awning control cable receiver adapted to be mounted on an interior building wall comprising a base plate, a cable receiving tube extending through said building wall and having one open end extending through said plate a cable projecting through said tube, a rim on said plate, an upstanding centered post on said plate and having a threaded opening therein, a cable locking flange adjacent the open end of said tube, a pair of cleats for engagement by a portion of said cable when slack, said flange and cleats being formed from said plate, a cover having walls

receiving and enclosing the entire structure of said plate, a screw carried by and projecting through the top of said cover, said screw being rotatable to engage or disengage the threads of said opening in said post.

7. An awning control comprising a cable, a cable guide and receiver adapted to be mounted on an interior wall of a building comprising a roller guide on the exterior face of said wall, a cable receiver on the interior face of said wall, a cable receiving tube extending through said wall, the ends of said tube opening at said guide and said receiver a cable projecting through said tube into said receiver, said receiver including a base plate, a central upstanding post on said plate, said post having a threaded end opening, cleats adjacent opposite ends of said plate, a cable locking flange adjacent the receiver tube end, said flange and cleats being arranged to lock said cable and secure the slack portion thereof, a cover for said receiver, walls of said cover enclosing the entire structure of said receiver and the portion of said cable secured to said cleats, and a screw carried by the top of said cover, said screw including an exterior head and an interior shank, said shank being engageable with the threads of said post opening.
